UNITED STATES PATENT OFFICE

AXEL H. STONE, OF DETROIT, MICHIGAN

AEROPLANE

Application filed June 18, 1928. Serial No. 286,164.

My invention relates to a new and useful improvement in an aeroplane, and particularly the body and wing construction thereof, as well as the mechanism for elevating the 5 aeroplane and preventing sudden downward movement thereof.

It is an object of the present invention to provide in an aeroplane a body construction in which a minimum wind resistance is pro- 10 vided.

Another object of the invention is the provision in an aeroplane of a body construction whereby an inclined deflecting portion at the forward end thereof may be afforded.

15 Another object of the invention is the provision in an aeroplane construction of a plurality of movable, swingably mounted elevating members and mechanism for moving said swingably mounted members in a body to effect a lifting power on the aeroplane body when moving in one direction, and so arranged and constructed as to offer a minimum 20 resistance when moving in the reverse direction.

25 Another object of the invention is the provision in an aeroplane of means for connecting a plurality of swingably mounted members to the motor of the engine for directing an elevating power against the body of the 30 aeroplane.

Other objects will appear hereinafter.

The invention consists in the combination and arrangement of parts hereinafter described and claimed.

35 The invention will be best understood by a reference to the accompanying drawings which form a part of the specification and in which,

Fig. 1 is a fragmentary front elevational 40 view of the invention.

Fig. 2 is a sectional view taken on line 2—2 of Fig. 1.

Fig. 3 is a fragmentary sectional view taken on line 3—3 of Fig. 2.

45 In the drawings I have illustrated the invention as provided with a body 7 having an inclined deflecting portion 8 at the forward end thereof, projecting diagonally outwardly 9 downwardly from which are braces 10 and 90 50 which serve as supports for the landing gear-

ing 11 and 12. The opposite wings of the aeroplane are of similar construction so that a description of one will suffice for both.

The brace 9 is braced by the rod 13 in which is interposed a turn buckle to the brace 14 which attaches to the undersurface of the wing 15. Extending outwardly from the upper surface of the body is a brace 16 which also serves to support the wing, and as shown in Fig. 2 the wing has a portion 17 tapered and secured to the body. A frame 18 extends forwardly from the tapered portion and serves as a support for a plurality of overlapping plates 19 which are held stationary but which are sufficiently resilient under supernormal strain to separate and allow the air to pass therethrough. The lower rail 20 of the frame is connected by the braces 21 and 22 to the portions 17 and 18 and by the portions 23, 24 and 25 to the upper rail of the frame so as to provide hub portions 26 and 27 which serve as bearings for crank shafts. A frame 28 is provided in which is swingably mounted a plurality of overlapping plates 26. This frame is connected to the cranks 31 and 32 of the crank shafts 33 and 34, the cheeks 29 and 30 extending to the cranks 31 and 32. Projecting upwardly from the rod or brace 35 are yokes 36 having the arms 37 and 38 in spaced relation and connected to the rail 18. Extending through these yokes is a shaft 43 which is connected to and driven by the shaft 44 of the engine. Fixedly mounted on the shaft 43 between the arms 37 and 38 of the yokes are double grooved sheave wheels 39. Fixedly mounted on the crank shafts 33 and 34 between the arms of the yokes are sheave wheels 40 which are connected by the chains 41 and 42 to the sheave wheels 39 or by any other suitable means.

As shown in Fig. 1 a plurality of the frames 28 are provided and the cranks on the crank shafts are so arranged that none of the frames are at the same elevation or same relative location on the same wing.

In operation when the engine is set into motion the frames 28 will be rotated so that the swingably mounted plates may serve to exert a lifting force on the aeroplane. Upon 100

the forward and downward movement of these frames 28 the plates 76 will be overlapped, as shown in Fig. 2, thus offering a resistance to the air, and upon the rearward and upward movement, these plates will swing into the position shown in Fig. 2 so as to offer little resistance, thus effecting a lifting power on the aeroplane and resembling to a great extent the wing movement of a bird.

It is believed evident that if desired a gear shaft may be used and the plates 76 used for propelling the machine as well as for lifting it.

With a construction such as this the easy and quick elevation of the aeroplane is effected and the safety of aeroplane riding considerably increased.

While I have illustrated and described the preferred form of my invention, I do not wish to limit myself to the precise details of structure shown, but desire to avail myself of such variations and modifications as come within the scope of the appended claims.

Having thus described my invention what I claim as new and desire to secure by Letters Patent is:

1. In an aeroplane of the class described having a body and a motor for propelling the same: a pair of braces projecting downwardly from said body at opposite sides thereof; a horizontally extending brace projecting outwardly from each of said downwardly extending braces; a plurality of yokes having spaced arms projecting upwardly from said horizontally projecting braces at spaced intervals; a shaft projecting laterally from each side of said motor and extending outwardly from said body and journalled in the arms of said yoke; a plurality of crank shafts projecting outwardly from each sides of said body; a plurality of frames; a plurality of swingably mounted plates carried by each of said frames and adapted for swinging into overlapping position at predetermined positions, each of said frames being mounted on the cranks on aligning cranks of said crank shafts between said yoke; and means connecting said crank shafts with said first mentioned shaft for effecting a rotation of said crank shafts upon rotation of said first mentioned shaft.

2. In an aeroplane of the class described having a body and a motor for propelling the same: a pair of braces projecting downwardly from said body at opposite sides thereof; a horizontally extending brace projecting outwardly from each of said downwardly extending braces; a plurality of yokes having spaced arms projecting upwardly from said horizontally projecting braces at spaced intervals; a shaft projecting laterally from each side of said motor and extending outwardly from said body and journalled in the arms of said yoke; a plurality of crank

shafts projecting outwardly from each side of said body; a plurality of frames; a plurality of swingably mounted plates carried by each of said frames and adapted for swinging into overlapping position at predetermined positions, each of said frames being mounted on the cranks on aligning cranks of said crank shafts between said yoke; a plurality of sheave wheels mounted on said first mentioned shaft between each set of yoke arms; a sheave wheel mounted on each of said crank shafts in alignment with a sheave wheel on said first mentioned shaft; and means for connecting said aligning sheave wheels for effecting rotation of said crank shafts upon rotation of said first mentioned shaft.

In testimony whereof I have signed the foregoing specification.
